(57) **CLAIM**

The ornamental design for an elastic terminal of micro RF connector, as shown and described.

DESCRIPTION

FIG. 1 is a perspective view of an elastic terminal of micro RF connector showing our new design;

FIG. 2 is a front side elevational view thereof;

FIG. 3 is a rear side elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a rear perspective view thereof.
